UNITED STATES PATENT OFFICE.

CANDACE WHEELER, OF NEW YORK, N. Y.

DESIGN FOR A CURTAIN FABRIC.

SPECIFICATION forming part of Design No. 17,045, dated December 28, 1886.

Application filed December 1, 1886. Serial No. 220,415. Term of patent 7 years.

To all whom it may concern:

Be it known that I, CANDACE WHEELER, a citizen of the United States, residing in the city, county, and State of New York, have invented and produced a new and original Design for the Ornamentation of Curtains, Draperies, and like Fabrics, of which the following is a specification, reference being had to the accompanying drawing, forming part hereof, and which shows a portion of a fabric so ornamented.

The design consists in the representation of lilies *a*. In connection with them are shown their supporting-stalks *b* and the long curved leaves *c* of the plant, all shown as confused and intermingled upon a background, *d*, of dots,

which are crowded together near the leaves, stalks, and flowers. A design of this character is continued over the entire surface of the fabric to be ornamented.

20

I claim—

The design for curtains, draperies, and like fabrics, consisting of the conventionalized representation of lilies, their supporting-stalks, and curved leaves confused upon the surface 25 of the fabric, and a background of dots crowded together near the leaves, stalks, and flowers, substantially as shown.

CANDACE WHEELER.
